ARTICLE COUNTER

Filed Jan. 31, 1927

UNITED STATES PATENT OFFICE

RAYMOND FITCH, OF TOLEDO, OHIO, ASSIGNOR TO THE CHAMPION NO-LEAK PAPER DISH COMPANY, OF TOLEDO, OHIO, A CORPORATION OF OHIO

ARTICLE COUNTER

Application filed January 31, 1927. Serial No. 164,765.

This invention relates to tally or counting apparatus more particularly as operated by production as contra-distinguished from machine operation.

5 This invention has utility when incorporated in counters for marking at predetermined quantity or production, as in the manufacture of food trays.

Referring to the drawings:

10 Fig. 1 is a fragmentary view, in side elevation, of an embodiment of a paper food tray forming machine having an embodiment of the invention incorporated therewith;

15 Fig. 2 is a fragmentary plan view of the counting device of Fig. 1;

Fig. 3 is a side elevation of the counting device;

Fig. 4 is a section on the line IV—IV, Fig. 3, looking in the direction of the arrow;

20 Fig. 5 is a section on the line V—V, Fig. 3, looking in the direction of the arrow;

Fig. 6 is a section on the line VI—VI, Fig. 5, looking in the direction of the arrow;

25 Fig. 7 is a view on the line VII—VII, Fig. 23, looking in the direction of the arrow;

Fig. 8 is a view looking into the device of Fig. 7; and

Fig. 9 is a section on the line IX—IX, Fig. 5.

30 Driven by belt 1 on pulley 2 machine 3 is supplied with sheet stock as paper 4. Such paper is blanked at press 5, and by the operation of plunger 6 against head 7 there is formed food tray 8 from such blank.

35 Actuated from plunger shaft arm 6', and in synchronism with the plunger 6, is rock arm 9 having terminal grab portions 10 effective, as the plunger 6 approaches its limit of descent, to engage tray 8 and thrust such

40 along guide 11 into chute 12 having side portions 13. This chute 12, as a discharge way, is accordingly supplied with the trays 8 as formed by the machine 3 through the intermediary of the transfer device.

45 The way 12, 13, is provided with cross-over frame 14 carrying top plate 15 and relatively yieldable lower plate 16 having up-standing ledge 17. This plate 16 is fixed with the plate 15 remote from the frame 14 and is yieldable to hang toward the guide 11 so that

as the articles 8 are thrust along such guide 11 they may ride past the ledge 17 and thus be maintained in the chute 12, 13, when the arm 9 is retracted to engage the succeeding article as produced.

55 Just toward the machine 3 from the ledge 17 and to be operated by an article as passing is a rocker or depending arm 18. This arm 18 is disposed clear of the transfer device 9, 10, so that in the instance no article is delivered by this transfer device there is no operation of this arm 18. Due to lack of paper stock or to failure of the stapling device to hold the article when the terminal grab portions 10 operate, the article is not 60 balanced by such quick movement to be directed toward the chute 12, 13, but is automatically culled to be thrown aside therefrom and thus not actuate the rocker 18.

65 This rocker 18 is fixedly mounted on stub 70 shaft 19 carried by bearing block 20 anchored by screws 21 with frame 22. This stub shaft 19 in the block 20 toward the frame 22 has fast thereon arm 23 having spring 24 normally holding pivoted dog 25 in inwardly 75 directed radial position. The shaft 19 has within rib portions 26, 27, spiral spring 28, one terminus 29 thereof being fixed with the shaft 19 and the arm 23, and the other terminus 30 being fixed with the block 20. There is 80 accordingly a tendency to hold this depending rocker 18 in a limit position with the arm 23 against an end of the rib 26 with the arm having a clearance for swinging in way 31 between the ribs 26, 27, at the lower portion. 85

At the upper portion, clearance 32 between the ribs 26, 27, permits mounting of holding dog 33 as cooperating with ratchet 34. This ratchet 34 is fast on shaft 35 in the housing 22 which shaft 35 has fixed thereon worm 36. 90

With the block 20 assembled with the frame 22, rocking of the arm 18 causes the dog 25 to cooperate with the ratchet 34 in this intermittent grip speed reduction operation of the shaft 35. With the arc of rocking for this 95 depending arm 18 such as to allow for ten oscillations in effecting one complete rotation of the shaft 35 and the double pitch worm 35 cooperating with worm wheel 37 so that twelve and a half rotations of the 100

worm 36 rotates the wheel 37 once, such complete rotation of the wheel 37 is thus effected upon the passage of 125 articles past the rocker 18.

5 In the housing 22 on shaft 38 fixed with the worm wheel 37 is insulation disk 39 carrying radial contact 40, in position in the plane of fiber washer or insulator 41. This insulator 41 is provided with radial opening 42 in which is disposed contact pin 43 normally urged by spring arm 44 against the periphery of the insulation disk 39. An insulation mounting 45 for this arm 44 is connected with electric current supply wire 46 from transformer 47 as a low voltage current supply in parallel with line 48 from such transformer 47. Line 48 extends to terminal 49 while the current from the line 46 as passing through the switch 40, 43, is conducted from the shaft 38 by terminal 50 and wire 51 to terminal 52 on frame 53.

10 This frame 53 is shown as having mounted therein a plurality of coils 54 of solenoids. These solenoids are energized upon closing of the switch 40, 43, pull down armature 55. This armature 55 has centrally therein plunger 56 fast therewith. The armature 55 is normally maintained elevated away from the solenoid coils 54 by spring 57. This 15 plunger 56 is of tubular form and has near its lower terminus opening 58 back of which is friction washer or rubber gasket 59 through which is projected marker, as crayon 60. Abutting this crayon 60 is cap 61 abutted by 20 threaded stem 62 operated through cap portion of plunger 56 having threaded assembly with the plunger. At the adjusted position for this threaded stem 62 in projecting the crayon 60, lock nut 63 may be operated.

25 In the operation of the device hereunder it is thus seen that as articles are shifted into the chute of tray way 12, 13, and before really entering such way each article tallies for effecting a counting herein, say as to a predetermined number of 125 trays. This 30 counting is effected by the action upon the rocker 18, the speed reduction mechanism at the intermittent grip device and the worm and worm wheel. This counting, as reaching the 125, or other predetermined number according to the gear and speed reduction, is effective through the switch 40, 43, for causing the marking crayon 60 to be thrust down into the path of the next succeeding food tray 8, thereby disclosing a mark thereon. 35 As the machine continues to have trays formed and delivered to the chute 12, 13, the switch 40, 43, is opened for a repetition of this cycle of operation upon the succeeding 40 count of 125 trays.

45 There is thus convenience for the packer to locate the 250 groupings of the trays 8 in the chute 12, 13, and transfer such identified number, say to a carton, for such articles 50 to be packed for shipment. There is thus

55 saved the time of the operator as to automatically inspected counted quantity of product independently of the operation of the machine in so far as there may be production from the machine.

60 What is claimed and it is desired to secure by Letters Patent is:

65 1. A way for receiving count identified articles, a reciprocable transfer device for definitely delivering articles to the way, a record identifying counter having an actuator disposed to be operated by the definitely delivered articles as shifted by the device into the way, said counter actuator being 70 not affected by device operation independently of effecting article delivery to the way, and a mounting locating the counter at the entrance of the way past which the transfer device is effective to move the article as receiving the mark.

75 2. A way for receiving count identified articles, a transfer device for delivering articles to the way, and a recorder for predetermined article number identification for assisting in article quantity isolation in the 80 way, including an article actuated counter, a switch connected to the counter, and a solenoid actuated article identifying recorder to be cut in by the switch.

85 3. A way for receiving count identified articles, a transfer device for delivering articles to the way, and a recorder for predetermined article number identification for assisting in article quantity isolation in the 90 way, including a counter actuatable by the rocker, a switch connected to the counter, and a switch controlled article identifying device.

95 4. An article counter comprising a rocker, a worm shaft, a ratchet transmission from the rocker to the shaft, a gear actuated by the shaft, a contact carried by the gear, and an additional contact to cooperate with the gear carrying contact as a switch, a circuit controlled by the switch embodying a solenoid, and a plunger recorder normally spring retracted and operated by the solenoid for effecting a record identification operation.

100 In witness whereof I affix my signature.

RAYMOND FITCH.
